ENGINE STARTER

Application filed October 24, 1929. Serial No. 402,237.

This invention relates to engine starters and more particularly to the inertia type of starter in which the starter pinion is mounted on a screw shaft so that it will be moved by the rotation of the shaft longitudinally thereof into mesh with an engine gear and will then be rotated with the shaft to drive the gear. In this type of starter when the teeth of the pinion abut the teeth of the gear, the pinion is supposed to be rotated by the shaft until its teeth clear the gear teeth, whereupon the axial movement of the pinion is continued until the latter is fully meshed with the gear. If the force tending to rotate the pinion be not sufficient to rotate it in the above mentioned case where the teeth of the pinion abut the teeth of the gear the pinion will be forced axially, by means of the screw shaft turning through the non-rotating pinion, against the gear and which will cause the screw shaft to be forced back to cramp or jam against its bearing and the engine crankshaft, on which the gear is carried, to be forced forwardly to jam against its bearings which will result in the starter motor being stopped. This is the well known jam of inertia or Bendix type of starters and is frequently of such intensity that the engine cannot be cranked by hand to relieve the jam. The object of the present invention is to provide a starter of this character which will overcome the above objectionable features.

We attain our object by providing an axially movable member, which may be the armature shaft of the starter motor or a sleeve thereon. The starter pinion is threaded on the member so that in case of collision between the pinion and the engine gear the thread connection between the pinion and the rotating member will cause the latter to be moved axially. This axial movement of the member is limited by a flange carried thereby which engages the side of the gear remote from the pinion. The gear is thus clamped between the pinion and flange so that the pinion cannot cause the armature shaft to be thrust against the bearings thereof nor can it move the gear axially to cause the crankshaft of the engine, which

shaft carries the gear, to jam against its bearings.

The constructions are hereinafter more fully described and illustrated in the accompanying drawings in which

55

Fig. 1 is a side elevation, partly in section, of part of our starter showing the parts in their normal or inoperative positions;

60

Fig. 2 a longitudinal section of part of the starter showing the pinion and flange in contact with the gear;

65

Fig. 3 an end elevation of the flange, pinion and part of the gear shown in Fig. 2;

65

Fig. 4 a detail in side elevation showing the pinion fully in mesh with the gear;

70

Fig. 5 a side elevation, partly in section, of a modified form of our starter; and

75

Fig. 6 a side elevation of the parts shown in Fig. 5 showing the pinion fully meshed with the gear.

70

In the drawings like numerals of reference indicate corresponding parts in the different figures.

1 is a starter motor provided with an axially movable armature shaft 2 which is journaled in the bearings 3, 4 and 5. On the shaft is threaded a pinion 6 which is moved along the shaft, by the rotation of the latter relative to the pinion, towards a gear 7 of the engine to be started. This gear is generally formed on or secured to the flywheel (not shown) of the engine and the flywheel is secured to the engine crankshaft (not shown).

75

Should the teeth of the pinion 6 register with the spaces between the teeth of the gear 7, the pinion will be moved directly into mesh with the gear. The gear teeth will prevent rotation of the pinion and the thread on the shaft 2 will feed the pinion along the shaft until it is fully meshed with the gear, which position is determined by an abutment formed as a flange 8 carried by the shaft. When the axial movement of the pinion is stopped the pinion will be rotated with the shaft to drive the gear.

80

In the case where the pinion teeth abut the gear teeth and the rotary movement of the pinion is stopped, the shaft will be threaded back through the pinion as in other inertia

starters but in our starter the shaft is prevented, by means of the flange 8 which engages the ends of the gear teeth opposite the ends engaged by the pinion, from retreating far enough to cramp or jam the starter motor bearings. The gear is thus frictionally clamped between the flange and the pinion so that the thrust against one side of the gear is equal to the thrust against the other side thereof. Heretofore in a case of this description, the pinion was pressed against the gear with such force that the armature shaft was axially forced in one direction until the thrust between the armature hub or collar 9 and the bearing 3 was sufficient to stop the motor. In addition to this jam there was also an axial movement of the gear in a direction opposite to that of the armature shaft which caused a jam between the crankshaft 20 of the engine and its bearings (not shown).

With our starter it is obvious that the flange 8 limits the axial movement of the shaft 2 so that the armature hub or collar 9 will not be thrust against the bearing 3, and that the gripping of the opposite sides of the gear prevents the pinion from moving the gear axially to cause a jam between the engine crankshaft and its bearings. The frictional grip on the flywheel gear should it not slip will turn the gear either to start the engine or permit the pinion teeth to slide into mesh with the gear teeth without damage to the parts.

In Figs. 5 and 6 we show a modified arrangement in which the armature shaft 2^a is mounted in the usual manner without allowance for axial movement. On the shaft 2^a is feather-keyed 2^b which is provided with a flange 9^a and has the pinion 6 threaded thereon. Should the pinion teeth collide with the gear teeth the sleeve will be threaded through the pinion to relieve the axial thrust between the pinion and gear. The flange 9^a limits this axial movement of the sleeve and prevents the end thereof from being thrust against the bearing 5. The manner of holding the gear from axial movement by the pinion is the same as that described for the preferred form of our invention.

In both the preferred and modified forms of the starters, the pinion 6 will be automatically de-meshed when the engine is started and before ejection takes place the member 2 or 2^b will be returned to its initial position. When the engine starts the speed of the gear drives the pinion at a greater speed than that of the shaft 2 or sleeve 2^b whereby the latter will be moved axially until a collar 10 or flange 9^a engages the bearing 5 or abutment 10^a respectively. The pinion will then be demeshed from the gear.

In Figs. 4 and 6 the pinion 6 is shown fully meshed with the gear 7 in the position it would take just before the gear is driven.

What we claim is:

1. In an engine starter drive the combination with a gear of an engine to be started, of a rotatable and axially movable member, a starter pinion threaded thereon whereby the pinion is moved longitudinally towards the gear by the rotation of the member and the member is moved axially in case the pinion collides with the gear; and means carried by the member for engaging the side of the gear remote from the pinion to limit the axial movement of the member. 70

2. In an engine starter drive the combination with a gear of an engine to be started, of a rotatable and axially movable member, a starter pinion threaded thereon whereby the pinion is moved longitudinally towards the gear by the rotation of the member and the member is moved axially in case the pinion collides with the gear; and a flange carried by the member for engaging the side of the gear remote from the pinion to limit the axial movement of the member. 75

3. In an engine starter drive the combination with a gear of an engine to be started, of a starter motor; an axially movable member rotatably driven by the starter motor; a starter pinion threaded on the member whereby the pinion is moved longitudinally towards the gear by the rotation of the member and the member is moved axially in case the pinion collides with the gear; and a flange carried by the member for engaging the side of the gear remote from the pinion if the latter fails to mesh with the gear whereby the pinion and flange will tend to clamp the gear between them. 85

4. In an engine starter drive the combination with a gear of an engine to be started, of a starter motor having an axially movable armature shaft journalled therein; a starter pinion threaded on the shaft for longitudinal movement toward the gear by the rotation of the shaft and for moving the shaft axially in case the pinion collides with the gear; and a flange carried by the shaft for engagement with the side of the gear remote from the pinion to limit the axial movement of the shaft whereby the gear will be clamped by the pinion and flange to prevent the armature shaft from jamming against its bearings. 95

Signed at Toronto, Canada, this 19th day of October, 1929.
